Primary Examiner — Ian Simmons*Assistant Examiner* — Keith Frank(74) *Attorney, Agent, or Firm* — DLA Piper LLP (US)(57) **CLAIM**

The ornamental design for a bottle, as shown and described.

DESCRIPTION

FIG. 1 is a perspective view of a bottle showing my new design;

FIG. 2 is a front view of the bottle;

FIG. 3 is a rear view of the bottle;

FIG. 4 is a right side view of the bottle;

FIG. 5 is a left side view of the bottle;

FIG. 6 is a top view of the bottle; and,

FIG. 7 is a bottom view of the bottle.

The broken lines on the bottom shown in FIGS. 1 & 7 illustrate the portions of the bottle that form no part of the claimed design. The broken lines in FIG. 6 represent the bounds of the claimed design and form not part thereof.
